J. FRANK COOPER AND CHARLES H. ZIMMERMAN, OF AKRON, OHIO, ASSIGNEES TO THE GOODYEAR TIRE & RUBBER COMPANY, OF AKRON, OHIO, A CORPORATION OF OHIO.

PARACHUTE.

1,412,800.

Specification of Letters Patent. Patented Apr. 11, 1922.

Application filed July 29, 1918. Serial No. 247,218.

To all whom it may concern:

Be it known that we, J. FRANK COOPER and CHARLES H. ZIMMERMAN, citizens of the United States, and residents of Akron, 5 Ohio, have invented new and useful Improvements in Parachutes, of which the following is a specification.

Our present invention relates to improvements in parachutes, and has for its principal object the provision of non-elastic tape 10 on the outside of the gore seam to replace the usual cord or rope heretofore provided.

A still further object is to provide an improved system of suspension in a parachute 15 whereby the usual bulky ropes are replaced by a series of strips of tape; thereby providing a lighter and stronger construction, and at the same time providing improved means of connection to the suspension cords 20 which more evenly distributes the strain throughout the parachute surface than has been done by the previously used rope systems.

The above and additional objects of a 25 similar nature, which will be hereinafter more specifically treated, may be accomplished by such means as are illustrated in the accompanying drawings, described in the following specification, and then more particularly pointed out in the claims which 30 are appended hereto and form a part of this application.

With reference to the drawings, wherein there has been illustrated a preferred embodiment of the invention as it is reduced 35 to practice, and throughout the several views of which similar reference numbers designate corresponding parts:

Fig. 1 is a side elevation of the parachute 40 as extended in use;

Fig. 2 is a sectional view on the line 2—2 of Fig. 1;

Fig. 3 is a fragmentary elevation of a portion of the perimeter; and

Fig. 4 is a sectional view on the line 4—4 of Fig. 1.

In the rope suspension systems as now commonly used, the various ropes are carried up through the seams of the parachute 50 surface or envelope and are fastened at a

common point at the top to the usually provided grommet. The splicing or fastening of the ropes to the grommet at the top makes a very bulky union which is objectionable as the parachutes are folded up and kept 55 in inoperative condition in a very small container, and the bulkiness of the usual different connections around the grommet at the top necessitates the use of a larger container. Also in threading the cord through the 60 seams, the seams of the parachute are likely to be stretched so that in practice the cords slip and move and prevent the strains along the seams from being evenly distributed.

In the present embodiment of our invention, we propose to do away with the usual cord system of suspension and provide a series of non-elastic strips of tape, designated in the drawing as 10, which are sewed along the gore seams 11 of the parachute 65 12. We find in practice that the most suitable size for the strip of tape is about one-half inch wide, but it is to be understood that we do not wish to be limited to the size, shape or the kind of material used. 75

At the upper end of the gore seams the strips of tape 10 are turned in with the fabric 12 over the usually provided grommet 14 and sewed.

In Fig. 4 of the drawings, wherein single 80 lines represent thicknesses of fabric and tape, we have illustrated diagrammatically, an arrangement of the tape reinforcement and the fabric of the parachute turned back around the rope grommet 14 as just described; and also have illustrated one way of finishing off the construction of the parachute around the perimeter, both on the outside and inside, with coverings of balloon fabric, now to be described. 85 90

At the outer edge of the parachute fabric the tape reinforcement is turned back on itself, as at 15, and a short piece of the same sized tape 16, is inserted between the two plies of the tape thus formed and produces a loop 17 which is sewed to the parachute fabric and which is adapted to receive the spliced eye 18 of the suspension cords 19. 95

There is also provided at the outer edge 100

- of the parachute fabric 12 a lap 20 about three inches wide which is turned up on itself to form a hem which is adapted to cover the eye splice 18 where it connects with the 5 reinforcing tape and also projects down for a distance on the suspension rope, or cords 19. This hem is reinforced by a continuous strip of doubled tape 21 which is placed in the lower part of the hem on the inside. 10 The hem is further reinforced by the insertion of another strip of tape 22 set on the inside of the before mentioned reinforcing tape 21 and is also doubled on itself extending up to the upper part of the hem. 15 At spaced intervals along the lower edge of the hem of the parachute fabric, the fabric is pierced to permit the suspension cords to be carried through, and at these particular points suitable grommets 23 are sewed 20 to the hem and reinforcing strip, in position to encircle the cords, thereby securely fastening the hem to the two reinforcing tapes.

When the various layers of fabric and tape are assembled in position over the eye spliced ends of the suspension cords, they are securely sewed in position by hand or otherwise, as shown at 24, the threads passing completely through the various thicknesses 30 and also the strands of the cords thereby securely binding the reinforcing tape and suspension cords, etc., in a secured position and as a unit.

From the foregoing it will be apparent 35 that we have produced a structure or reinforcement that may be easily and quickly put together and which will be lighter and much stronger. Although we have illustrated and described a single reinforcement sewed along the gore seams on the outside 40 of the parachute proper, we may also provide one or more strips of tape along the inside of the parachute, and we may also provide auxiliary layers or suitable covering 45 and binding strips without departing from the spirit and scope of the invention defined in the appended claims.

What we claim is:

1. A parachute provided with strips of non-elastic tape secured along the gore seams thereof, the outer end portions of said strips of non-elastic tape being turned back and joined to the outer edge portion of the parachute fabric to form loops. 50
2. A parachute having strips of non-elastic fabric secured along the gore seams thereof, suspension cords, and means for connecting said suspension cords to said strips of non-elastic fabric. 58
3. A parachute provided with strips of non-elastic tape secured along the gore seams thereof, the outer end portions of said strips of non-elastic tape being turned back and joined to the outer edge portion of the para- 60

chute fabric to form loops, a hem secured 65 to the outer edge portion of the parachute fabric, and suspension cords passed through said hem and connected to said loops.

4. A parachute having a grommet secured at the inner edge portion of the parachute 70 fabric, and provided with strips of non-elastic tape secured along the gore seams and passed over said grommet and secured to the parachute fabric.

5. A parachute having a grommet secured 75 at the inner edge portion of the parachute fabric, and provided with strips of non-elastic tape secured along the gore seams and passed over said grommet and secured to the parachute fabric, the outer end portions 80 of said strips of non-elastic tape being turned back and joined to the outer edge portion of the parachute fabric to form loops for the purpose set forth.

6. A parachute having a grommet secured 85 at the inner edge portion of the parachute fabric, and provided with strips of non-elastic tape secured along the gore seams and passed over said grommet and secured to the parachute fabric, the outer end portions 90 of said strips of non-elastic tape being turned back and joined to the outer edge portion of the parachute fabric to form loops, a hem secured to the outer edge portion of the parachute fabric, and suspension 95 cords passed through said hem and connected to said loops.

7. A parachute having a grommet secured at the inner edge portion of the parachute 100 fabric, and provided with strips of non-elastic tape secured along the gore seams and passed over said grommet and secured to the parachute fabric, the outer end portions of said strips of non-elastic tape being turned back and joined to the outer edge portion 105 of the parachute fabric to form loops, a hem secured to the outer edge portion of the parachute fabric, a reinforcing strip disposed in said hem, grommets secured to the hem and reinforcing strip, and suspension 110 cords having eye splices connected to said loops, said suspension cords passing through the last mentioned grommets, and said eye splices being secured to said hem.

8. A parachute comprising fabric sections 115 secured together by radial gore seams, a non-elastic tape secured along each gore seam said tapes having their respective outer ends provided with a looped portion, a hem around the outer edge of the parachute for 120 enclosing the looped portions, and load supporting elements suspended from the looped portions, said elements passing through the hem and being connected thereto.

9. A parachute comprising fabric sections 125 secured together by radial gore seams, a non-elastic tape secured along each gore seam said tapes having their respective outer ends

provided with looped portions, a hem around the outer edge of the parachute for enclosing the looped portions, reinforcing strips for the hem, and load supporting elements suspended from the looped portions, said elements passing through the hem and being connected thereto.

5 In witness whereof, we have hereunto

signed our names in the presence of two subscribing witnesses.
